PEGBOARD HOOK GUARD

Stanley J. Valiulis, Rockford, Ill., assignor to Southern Imperial, Inc., Rockford, Ill.

Filed Aug. 6, 1974, Ser. No. 495,223

Term of patent 14 years

Int. Cl. D8—99

U.S. Cl. D8—263

FIG. 1 is a perspective view of a pegboard hook guard incorporating my new design.

FIG. 2 is a top plan view of the guard.

FIG. 3 is a side elevational view of the guard.

FIG. 4 is a cross-sectional view taken along the line 4—4 of FIG. 2.

FIG. 5 is a front elevational view of the guard.

FIG. 6 is a rear elevational view of the guard.

I claim:

The ornamental design for a pegboard hook guard, as shown.
